DIAPER CLEANER

James E. Wilson, 740 Sammoner Ave., Florence, Ala.
Filed Mar. 16, 1959, Ser. No. 799,530
2 Claims. (Cl. 15—105)

This invention relates to a sanitary washing apparatus, and it deals more particularly with an instrument for the easy removal of solid foreign matter from an infant's diaper in pre-washing prior to laundering.

The primary object of the invention is to provide a convenient means for cleaning an infant's diaper or like garment, preparatory to laundering, in a sanitary manner, and with little, if any, necessity of contact with the soiled part by the hands.

In connection therewith, it is a salient feature of my invention that I have provided an instrument wherewith a diaper may be scraped, during pre-rinsing in a commode, and which also may be employed to wring the diaper free of excess water without the necessity of the use of the hands for wringing.

The average American home today uses a laundromat or a diaper service, or has special provisions for laundering soiled diapers in the home. It is customary to pre-rinse or prewash diapers before submitting them to the usual laundering. This is true whether or not the diapers, or under garments of infants, are washed in the home or sent to a diaper service. Diaper service companies require their customers to clean and rinse these articles and substantially remove all stains as a necessary health measure.

Further, it has been found by health authorities that the only practical way to prevent epidemic diaper rash is through strict enforcement of home sanitary measures prior to washing in a public laundry.

The most common method of handling diapers calls for dipping a diaper soiled with fecal matter in the bowl of the commode filled with water, where the solids are scraped off with some instrument, and the diaper is then wrung free of excess water with the hands. Afterward, the diaper is placed in a special container preparatory to laundering. It can readily be seen that the use of the hands in this operation is an unsatisfactory method of handling.

Accordingly, I have provided an instrument of the character described herein having a scraping edge, for use in removing solid fecal matter from a diaper, which also is formed with a special configuration of its surface to provide a recess through which, by articulation, a diaper may be wrung substantially free of water without the usual necessary use of the hands. In this connection, I have also provided means for grasping a submerged diaper with the same advantages.

In the accompanying drawings, which form a part of the instant specification, and are to be read in conjunction therewith, and in which like reference numerals are employed to indicate like parts in the various views:

FIG. 1 is a plan view of the article.

FIG. 2 is a sectional view taken along the lines 2—2 of FIG. 1 in the direction indicated.

FIG. 3 is a plan view partially broken away of a modification of the invention.

FIG. 4 is a sectional view taken along the lines 4—4 of FIG. 3 in the direction indicated.

FIG. 5 is a sectional view of a standard type commode to show the scraping operation in use of the invention.

FIG. 6 is a sectional view of a commode showing the use of the invention in wringing.

Referring more particularly to the drawings, it will be seen that my invention comprises essentially an elongated bar A having one end shaped to form a handle 1, with the other end of the bar reversely curved to provide a

2

scraping head 2, having an inner concave face 3 and an outer convex scraping edge 4.

The configuration of the scraping head 2 is such that it comes substantially to a point at its outer end, as shown in the embodiment illustrated in FIG. 1. As can be seen from FIGS. 1 and 2, the scraping edge 4 is provided with upper and lower beveled surfaces 4a and 4b, respectively.

The concave inner face 3 is tooled to provide a smooth rounded face, as can readily be seen from FIG. 2. The handle end of the instrument is provided with a hole 6, such that the same can be hung in a convenient place when not in use.

I have found it desirable, but not essential, that this instrument be made of a plastic material, such that the same may be easily stamped or cast and the faces of the head tooled and beveled as shown.

As can be seen from FIG. 5, the instrument of my invention is used in connection with a standard type of toilet bowl 7. This type of bowl, found in the usual commode, is provided with a water bowl 8, having at its upper end a rounded lip 9. The bowl is provided with a forward baffle wall 10 descending into a recess 11 communicating with an outgoing water passage 12 formed with a baffle wall 13, further communicating with a trap 14 passing into the sewer line 15. The bowl is also provided with an intake passage 17 communicating with the intake line through opening 18 and the bowl through opening 19. This passage is of course suitably vented through an opening 20 as shown.

The use of this invention is relatively simple. In normal operation the toilet bowl 8 is filled with a level of water 22 which rises to a substantial level on the baffle wall 10. A soiled diaper is grasped by one end with the diaper 25 being dipped into the bowl and sloshed around in the water to loosen the material adhering thereto. With the end of the diaper held in the hand, with the principal soiled surface of the diaper resting on the forward baffle wall 10 and beneath the surface of the water, the instrument of my invention is used, as indicated in FIG. 5, with the convex edge of the head 4 being used to scrape the surface of the diaper beneath the surface of the water, as shown. During this operation the commode would be flushed several times to wash away all of the soiled matter.

As soon as the diaper 25 is substantially free from solid matter and stains, after repeated washings and scrapings, the diaper is then lifted over to the edge of the toilet bowl, as indicated in FIG. 6. At this point, the pointed end of the head of the instrument is hooked under the edge of the lip 9 of the toilet bowl as shown in FIG. 6. This operation is preferably accomplished on the edge of the toilet bowl. With the pointed end of the instrument hooked under the edge of the lip of the toilet bowl the naturally constricted wet portion of diaper is brought into the recess 3 of the head of the instrument, and the instrument articulated outwardly relative to the bowl, to squeeze this portion of the diaper. The diaper is then drawn upwardly through the recess and against the concave surface 3, with the instrument being held firmly against the diaper, such that the diaper in this operation is squeezed or wrung substantially free from water as the diaper is withdrawn from the bowl.

It can readily be seen that by articulation of the instrument, as the diaper is drawn through the recess 3, the diaper can be wrung free of water just as effectively as can be done with the use of both hands.

Due to the peculiar structure of some toilet bowls, I have found that a modification of my invention may be effectively used as indicated in FIG. 3 of the drawings. Referring more particularly to FIG. 3, it can be shown that a modification of the invention may be made wherein the head 2 of the instrument is formed with the con-

cave recess 3 formed more arcuate with a projection 2a providing a substantially crescent shaped head as indicated. In this modification, the surface 3 is notched at its outer end to form a projecting shoulder 3a.

It can readily be seen that with this modification the instrument may be used with a toilet bowl having a smaller lip, and, by articulation, in the twisting of the instrument or rotating the same inwardly a stronger squeezing or wringing action may be exerted upon the surface of the diaper.

With either embodiment of the invention, it can also be seen that the pointed end of the head may be used to pick up a diaper which has become totally submerged beneath the surface of the water in the toilet bowl.

It will be readily apparent that my invention has many advantages. This invention makes it possible for a person preparing a diaper for laundering to handle the same with the minimum use of the hands. It is possible, first, to grasp a diaper with the pointed end of the instrument, enabling the user to then seize the diaper by one of its corners. The diaper may then be submerged in the water without wetting the hands. Bringing the same to the side of the toilet bowl, or preferably, the front and face of the toilet bowl, the end of the instrument may be used for the purpose of scraping the surface of the diaper free of all solid material. In this operation, again, it is not necessary to allow the hands to come in contact with the water in the bowl. As soon as the diaper is substantially free from solid waste and clean, the end of the diaper may be brought over to the edge of the toilet bowl and, by use of the instrument as described, the diaper may be wrung free from water.

In the manufacture of this instrument it is necessary that the inner surface of the concave recess 3 be completely rounded in order to provide a smooth surface against which the diaper may be drawn in the wringing operation. Since diapers are not made of very strong material, the rounding of the surfaces mentioned prevents the tearing of the fibers of the material. The convex surface of the head 4 should be beveled in order to obtain more efficient scraping, but this is not necessary if it is desired to manufacture the instrument with a more simple design.

The instrument is simple in design and economical to manufacture. It may be made from any of the well known semi-rigid plastic materials, or if desired, can be manufactured of metal or, where necessary, of wood. The design of the instrument is such that it can be used by either a left handed or a right handed person.

It is within the scope of this invention that various materials may be used for the manufacture of this article,

and that either of the embodiments shown may be employed.

From the foregoing it will be seen that this invention is one well adapted to attain all of the ends and objects herein before set forth, together with other advantages which are obvious and which are inherent to the device.

It will be understood that certain features and sub-combinations are of utility and may be employed without reference to other features and sub-combinations.

This is contemplated by and is within the scope of the claims.

Inasmuch as various modifications of the structure may be made without departing from the scope of the invention, it is to be understood that all matter herein set forth or shown in the accompanying drawings is to be interpreted as illustrative and not in a limiting sense.

Having thus described my invention, I claim:

1. A diaper cleaner of the character described comprising an elongated flattened bar having one end shaped to form a straight, substantially narrow lengthwise handle, means to hold a diaper against the edge of a toilet bowl and to wring said diaper, said means comprising a reversely bent portion shaped to a point to provide a substantially crescent-shaped head with opposite parallel planar surfaces, and having one side of said head shaped to provide a smooth-edged concave wringing surface for squeezing and wringing a diaper drawn tightly thereupon, and the other side of said head shaped to provide a convex projection thereof having inwardly beveled planar surfaces to form a substantially sharp scraping edge.

2. A diaper cleaner of the character described in claim 1, wherein a portion of said handle adjacent said head is extended therefrom projecting into the concave portion of said head to provide a substantially semi-circular arcuate configuration to said concavity.
